BOTTLE CAPPING DEVICE

Thorvald Petersen, Erie, Pa., assignor to R. G. Wright & Co., Buffalo, N. Y.

Application May 31, 1933, Serial No. 673,576

18 Claims. (CL 226—92)

This invention relates to improvements in devices for placing caps on bottles, and particularly for use in connection with the placing of paper caps into seats formed in the necks of bottles, 5 such as are commonly used for milk.

Some objects of this invention are to provide a bottle capping device of this kind of improved and simplified construction which is positive and accurate in its operation; also to provide a capping device of this kind which is so constructed that it can be readily taken apart for cleaning or other purposes; also to provide a bottle capping device which is so constructed that even after severe use and wearing of the parts, it will 10 still function with accuracy; also to provide a bottle capping device in which a single holding or locking member supports all of the movable parts in correct relation to the housing of the capper, and which when moved into released position permits the movable parts to be removed 15 from the housing; and also to provide a capping device with a part which can be adjusted to compensate for wear of the device to insure accurate operation of the capping device for a 20 long period of time.

Other objects of the invention are to construct a bottle capping device in which no springs are used to produce tension or compression for assisting the action of moving parts so as to thereby provide a device which requires much less effort to operate than such devices having springs therein, and whereby the invention can be successfully used for capping paper bottles without damage thereto; also to construct a capping device which can be used either for capping glass bottles or paper bottles as desired; also to provide an adapter for use with the improved capper to enable the device to be quickly changed for use with either glass or paper bottles, or 25 which will permit the capper to be used with bottles having necks or mouths of slightly different diameters or sizes; and also to improve bottle capping devices of this kind in other respects hereinafter specified.

45 In the accompanying drawings:

Fig. 1 is an elevation of a bottle capping device embodying this invention;

Fig. 2 is a top plan view thereof;

Fig. 3 is a fragmentary elevation thereof, partly in section, on line 3—3, Fig. 4, on a larger scale than Figs. 1 and 2;

Figs. 4 and 5 are sectional plan views thereof, on lines 4—4 and 5—5 respectively of Fig. 3;

Fig. 6 is a perspective view of the cap feeding 55 member of the capping device;

Fig. 7 is a fragmentary sectional elevation on line 7—7, Fig. 3;

Fig. 8 is a fragmentary vertical section similar to the lower portion of Fig. 3, showing in broken and full lines respectively two intermediate positions in the application to the capping device of an adapter for use in capping paper bottles;

Fig. 9 is a similar view, taken on line 9—9, Fig. 4, showing the adapter in operative position;

Figs. 10 and 11 are a plan view and a side elevation respectively of the adapter.

My improved bottle capping device includes a housing 10, which is preferably, though not necessarily, formed in a single piece and is provided with the usual downwardly and outwardly flaring or tapered bottle alining flange or skirt 11 adapted to fit over and center the upper end of the bottle A to be capped, as clearly shown in Fig. 3. The housing is also provided with a guide portion or aperture 12 arranged to guide a plunger 15 in its movement toward and from the upper end of a bottle to place a cap therein. The guide portion 12 in the construction shown is in the form of a cylindrical bore in the housing, but it will be obvious that the form of this guide portion may differ, as desired. The plunger, in the particular construction shown, is provided with a handle 16 which may be formed integral with or suitably secured to the plunger 15, and when the capping device is actuated by a machine instead of by hand, it will be obvious that the handle 16 may be replaced by suitable means connecting the plunger with a part of a mechanism for imparting reciprocatory movement to the plunger.

The housing is also provided with a suitable receptacle or magazine from which caps B can be fed one at a time in position to be placed on the bottles by the plunger. In the particular construction shown, the housing is provided with a split cylindrical portion 18 which may be an integral part of the housing or secured thereto and which is provided with a clamping bolt 19. The cylindrical portion or aperture 18 forms a cap magazine or receptacle and is adapted to receive the lower end of a tube or container 20 for caps and by adjusting the clamping screw 19, the cap magazine or aperture 18 can be readily adjusted to clamp the lower end of the cap containing tube 20 with the desired tension to maintain the tube in accurate alinement with reference to the housing. The caps may, of course, be placed into the cap magazine without clamping the tube 20 in the magazine.

55

The feeding of the caps B one at a time from the lower end of the cap magazine 18 to the plunger guide aperture 12 of the housing may be effected by means of a feed plate or member 5 of any suitable kind which has a part that moves back and forth between the bottom of the cap magazine and the aperture 12. In the particular construction shown, this feed member is in the form of a plate 22 which is more or less arc-shaped and which is adapted to swing about an upright pivot. This feed member is provided at one end thereof with a depressed or seat portion 23 into which a single cap may drop from the bottom of the magazine 18 when this seat portion is positioned under the cap magazine 18, as shown in Figs. 1 and 2. When this feed plate is at the opposite limit of its movement, as shown in Figs. 3 and 4, it positions a cap in alinement with the plunger 15. The feed plate is provided 10 with an upright pivot member 25 which, in the particular construction shown, is rigidly and permanently secured to the feed plate 22 and is pivotally arranged in another aperture 26 formed in the housing 10. 15

In order to produce the desired movement of the feed plate 22, a suitable connection between the reciprocating plunger 15 and the pivot member 25 is provided and in the construction shown, the plunger 15 is for this purpose provided with 20 a laterally extending post or pin 28 which extends through an upright slot or channel 29 in the housing 10, this slot connecting the aperture 12 in which the plunger 15 reciprocates and the aperture 26 in which the pivot member 25 is arranged. To produce oscillatory movement of the pivot member 25, this member in the particular construction shown is provided with a cam-shaped part or groove 30 in the cylindrical surface thereof and into which the end of the pin 28 or post 28 of the plunger extends. The cam-shaped groove 30 is so formed in the particular construction illustrated that when the plunger is at or near the upper end of its movement, the cap receiving seat 23 of the feed plate 22 is in 30 a position to place a cap in alinement with the aperture 12 of the plunger, and when the plunger is at the lower end of its movement to press the cap into the neck of the bottle, this seat 23 will be in a position to receive a cap from the 35 magazine aperture 18. It will be noted too that the upper and lower ends of the cam slot are substantially vertical for a considerable distance, so that the feed plate reaches the ends of its movement before the plunger has moved to the 40 limits of its movement. The advantage of this construction is that as the curved portions of the cam slot 30 are worn by continued use of the capping device, no inaccuracy of the positioning of the caps results, since the wear will 45 not extend to the entire vertical portions of the cam slot, the end portions of which are subjected to substantially no friction by contact with the end of the pin or post 28. Any other suitable or desired connections between the plunger and the pivot member 25 to effect oscillation thereof 50 may be employed, and if desired, the pivot member may be differently connected with the feed plate 22 to impart movement thereto.

In order to support the various parts of the 55 capping device in their correct relations to the housing and to each other, a locking and adjusting plate or member 35 is preferably employed, one end of which is adapted to engage on the under side or face of a head 36 formed on a part 60 of the pivotal member 25. In the particular con-

struction shown, this head is formed at the upper end of an annular groove or recess 37 into which an end of the retaining plate 35 extends, the retaining plate having this end bifurcated to provide a more extended bearing of this plate against the under face of the head 36. This plate is suitably secured to the upper end of the housing 10, for example, by means of a set screw or the like 38 which extends through a slot 39 in the plate 35 and engages with a threaded hole in the upper end of the housing 10. When it is desired to remove the feed plate from the housing, it is only necessary to loosen the bolt or set screw 38 and to slide the locking plate 35 lengthwise of the housing to a sufficient extent to cause this plate to disengage the head 36 of the pivoted member 35, whereupon this pivot member may be moved downwardly out of its aperture 26 in the housing, the feed plate 22 for this purpose being turned into a position in which the same can be moved downwardly clear of the skirt 11 and other parts of the housing. 10

For the sake of compactness and light weight, the centering skirt or flange 11 is notched or cut away at 11^a see Figs. 1, 3, 5 and 8, to enable 25 the pivot portion 25 of the feed means to pass said part 11 in the described downward movement of the pivot member. The notch or opening 11^a serves also a further purpose, as will be later explained. 30

It will be noted in referring to Figs. 2 and 3 that the retaining plate 35 also extends across the slot 29 connecting the apertures 12 and 26 and, consequently, so long as the plate 35 is in its operative position, as shown in Figs. 1 to 3, this plate also forms a stop for the upper limit of the movement of the plunger 15, since the post 28 of this plunger engages the plate 35 at the upper limit of its movement. Consequently, upon movement of the plate 35 into inoperative position, the plunger 15 can also be withdrawn from the housing. When the head 36 of the pivot member is of the same diameter as the body portion of this member, the head can be provided with a notch or recess 42 forming substantially an extension of the cam groove 30, to permit the pin or post 28 to pass the head 36. 45

The retaining plate 35 is preferably so formed as to be adjustable to correctly hold the pivot member 25 and the feed plate 22 secured thereto in correct relation to the housing to insure accurate feeding of caps. This is done by providing on the lower face of the plate 35 a boss or pivot 40 and by providing at the end of this plate farthest removed from the pivot member 25 a set screw 41 engaging in a threaded hole in the plate 35. It will be obvious that by turning the set screw 41, the clamping bolt or screw 38 when tightened will cause the plate 35 to rock about the pivot or boss 40 to a greater or less extent, depending upon the position of the set screw 41, so that the other end of the plate 35 which engages the pivot member 25 will occupy a position depending upon the adjustment of the set screw 41. For example, as the parts of the feeding mechanism wear, and it becomes necessary to raise the end of the holding plate 35 which engages the head 36 of the pivot member, the set screw 41 is turned in a direction to permit its end of the locking plate 35 to move closer toward the top of the housing 10 when the screw or bolt 38 is tightened. By means of this arrangement, the proper adjustment of the feed plate can be easily effected at any time, so that wear 55

of the parts of the mechanism can be compensated for.

Since the caps are fed to the plunger while the same is in its upper position, means must be provided for receiving and holding these caps while the feed plate 22 swings back into a cap receiving position. In the case of some types of caps, the caps may fit with sufficient tightness into the lower portion of the aperture 12 of the plunger guide so that no further means for holding the caps are necessary. If, however, caps are used which do not fit closely within the bore or aperture 12, a resilient cap holding device may be used, such for example as a spring actuated pressure finger 44 arranged in a recess in a portion of the housing 10, the presser finger being yieldingly urged into its cap holding position by means of a spring 45, the tension of which may be adjusted by a screw 46 threaded into the aperture formed in the wall of the housing 10. The guide aperture 12 for the plunger 15 is preferably slightly smaller in diameter than the caps, and the guide aperture is, therefore, of increased diameter at the lower portion 48 thereof which receives the caps. By locating the finger 44 in the part 48 of enlarged diameter, this finger will engage the edge of a cap and press the same against the opposite wall of the aperture 48 for frictionally holding the cap until the same is pressed downwardly by the plunger 15, and the spring finger 44 therefore does not extend into the path of movement of the plunger 15.

In the use of the capping device, the raising of the plunger for lifting the capping device from a bottle or for carrying the device into operative relation to a bottle, causes the feed plate to move into the cap delivering position as shown in Figs. 3 and 4. After the capper has been positioned on a bottle, the plunger is depressed to force the cap held by the spring plunger 44 into engagement with the seat on a bottle neck and this downward movement of the plunger causes the feed plate 22 to swing into a position under the cap magazine to receive another cap.

As will be seen upon referring to Fig. 3, the inner flaring wall of the skirt or centering flange 11 terminates at its upper end in a seat 50 the diameter of which corresponds to, and engages the outside diameter of, the mouth of a glass milk bottle, the wall of said mouth portion being of considerable thickness, as usual. It is obvious that said seat 50 would not function in centering the mouths of paper bottles such as are now used for milk, buttermilk, and other products, since, while the cap receiving seat of these bottles is of the same standard diameter as the seats of the glass bottles, the outside diameter of the mouths thereof is much less than the corresponding dimension of the glass bottles.

To enable my capping device to be used for capping paper bottles I therefore provide an adapter or part which can be readily applied to or removed from the skirt portion 11, see Figs. 8-11. The adapter, as shown, preferably comprises an annular tapering member 51, formed for example from sheet metal, and which may be positioned within the skirt or flange 11 of the capper in engagement with the inner face thereof. The upper and smaller end of the adapter is of approximately the size as the outside diameter of the top or mouth 52 of a paper bottle, see Fig. 9, and this portion of the adapter extends within the seat 50. The lower edge 53 of said adapter is preferably flanged outwardly to

abut against the corresponding edge of the skirt 11, the adapter being releasably or detachably supported in this position by any suitable means.

The means shown for this purpose comprises a pair of diametrically opposed and inwardly bent fingers or hooks 54 the ends of which rest upon the outside wall of the skirt 11, see Fig. 8. To apply the adapter, one of the hooks 54 is positioned over the edge of the part 11 at the side opposite the notch 11a before mentioned, and while so placed the other hook may be passed upwardly through said notch, as shown in Fig. 8, to permit the flange 53 to engage the skirt 11. By now rotating the adapter through a part of a turn the two hooks 54 will be engaged upon the outer wall of said skirt to retain the adapter in operative position.

Since the capper described has no springs connected with the operation of the plunger or cap feeder, the device can be operated with much less effort than cappers provided with such springs, as the resistance offered by such springs requires much extra effort to overcome the same. For this reason it is possible to use the present capper to apply caps to paper bottles without the slightest injury to such bottles, since a relatively light pressure is required in positioning the caps.

I claim as my invention:

1. A capping device including a housing, a plunger arranged to reciprocate on said housing, a feed member for placing caps into operative relation to said plunger, a pivot member connected with said feed member and having a cam portion, and a post secured to the side of said plunger and having its outer end extending laterally into cooperating relation to said cam portion to impart oscillatory motion to said pivot member in accordance with the reciprocatory movements of said plunger.

2. A capping device including a housing having a pair of upright apertures connected by a longitudinal slot, a plunger arranged to reciprocate in one of said apertures, a feed plate for placing caps into operative relation to said plunger, a pivot member connected with said feed plate and arranged in said other aperture and having a cam groove in the outer face thereof, and a pin secured to said plunger and extending through said slot into said groove to impart oscillatory motion to said pivot member.

3. A capping device including a housing, a plunger guided by said housing to reciprocate, a feed member for feeding caps into operative relation to said plunger, a pivotal member for imparting movement to said feed member and journaled on said housing and having a cam-shaped portion on the periphery thereof, a laterally projecting part on said plunger and extending into engagement with said cam-shaped portion to impart oscillatory motion to said pivotal member when said plunger reciprocates, and yielding means which hold a cap in operative relation to the plunger and to which a cap is delivered by said feed member.

4. A capping device including a housing having three upright apertures, a plunger arranged to reciprocate in one of said apertures, another of said apertures serving as a magazine for caps, a movable feed member for feeding caps from said magazine to said plunger, a pivotal member arranged to oscillate in the third aperture to impart movement to said feed member, the apertures for said plunger and said pivotal member being connected by a slot, and a part on said plunger extending through said slot and engag-

ing said pivotal member to impart oscillatory motion thereto.

5. A capping device including a housing, a plunger guided by said housing to reciprocate, a feed member for feeding caps into operative relation to said plunger, a pivotal member for imparting movement to said feed member and journalled on said housing, and having a cam-shaped portion on the periphery thereof, a laterally projecting part on said plunger and extending into engagement with said cam-shaped portion to impart oscillatory motion to said pivotal member when said plunger reciprocates, and a part removably secured to said housing and engaging said pivotal member to confine the same in operative relation to said housing and limiting the movement of said plunger relatively to said housing.

6. A bottle capping device including a housing, a plunger guided for reciprocatory movement on said housing, a pivot member mounted to oscillate on said housing and having a cam portion formed thereon, a cap feed member operated by said pivot member, a magazine for caps on said housing from which caps are fed one at a time by said feed member into operative relation to said plunger, a post secured to said plunger and extending into operative relation to said cam portion for oscillating said pivot member when said plunger reciprocates, and a retaining member removably mounted on said housing and engaging said pivotal member to hold the same against endwise movement relatively to said housing and also arranged in the path of movement of said post to limit the movement of said plunger out of operative relation to said housing.

7. A bottle capping device including a housing having a pair of upright apertures formed therein, a plunger movable vertically in one of said apertures, a pivot member arranged to oscillate in another of said apertures and connections between said plunger and said pivot member for producing oscillation of said pivot member when said plunger reciprocates, a magazine for caps, means actuated by said pivot member for feeding caps one at a time from said magazine into operative relation to said plunger, a retaining plate mounted on said housing and engaging said pivot member to prevent endwise movement of the same in its aperture in said housing, a part on said plunger adapted to engage said retaining plate for holding said plunger in operative relation to said housing, and means for releasably securing said retaining plate to said housing to permit said retaining plate to be moved out of operative relation to said pivot member and said part of said plunger.

8. A bottle capping device including a housing having a pair of apertures, a plunger arranged to reciprocate in one of said apertures, a cap feeding device having a pivot member arranged in the other aperture, said housing having a slot connecting said apertures, means securing said plunger and extending through said slot for turning said pivot member, a retaining member arranged on said housing and engaging a part of said pivot member to prevent endwise movement thereof relatively to said housing, and means for adjusting said retaining member to support said pivot member in different relations to said housing.

9. A bottle capping device including a housing having a pair of upright apertures formed therein, a plunger movable vertically in one of

said apertures, a pivot member arranged to oscillate in another of said apertures and connections between said plunger and said pivot member for producing oscillations of said pivot member when said plunger reciprocates, a magazine for caps, means actuated by said pivot member for feeding caps one at a time from said magazine into operative relation to said plunger, a retaining member mounted on the upper portion of said housing and having a part engaging said pivot member to limit endwise movement of the same relatively to said housing, and means for adjusting said retaining member to cause a portion thereof engaging said pivot member to support said pivot member in different relations to said housing.

10. A bottle capping device including a housing having a pair of upright apertures formed therein, a plunger movable vertically in one of said apertures, a pivot member arranged to oscillate in another of said apertures and connections between said plunger and said pivot member for producing oscillation of said pivot member when said plunger reciprocates, cap feeding means actuated by said pivot member, said pivot member having a head extending beyond the upper end of its aperture, a retaining member mounted on the upper portion of said housing and having a part engaging said head to retain said pivot member in said housing and for effecting axial adjustment thereof, and means for adjustably securing said retaining member on said housing.

11. A bottle capping device including a housing having a pair of upright apertures formed therein, a plunger movable vertically in one of said apertures, a pivot member arranged to oscillate in another of said apertures and connections between said plunger and said pivot member for producing oscillation of said pivot member when said plunger reciprocates, cap feeding means connected with said pivot member at the lower portion thereof, a head at the upper portion of said pivot member, a retaining member arranged on the upper portion of said housing and engaging said head, means for releasably securing said retaining member to said housing to permit removal of said pivot member from its aperture, and means on said retaining member for adjusting the portion thereof engaging said head to compensate for wear.

12. A bottle capping device including a housing having a pair of upright apertures formed therein, a plunger movable vertically in one of said apertures, a pivot member arranged to oscillate in another of said apertures and connections between said plunger and said pivot member for producing oscillation of said pivot member when said plunger reciprocates, cap feeding means actuated by said pivot member, a plate engaging the upper portion of said pivot member for preventing movement of said pivot member out of its aperture, said plate having a slot, and a bolt extending through said slot and secured in said retaining plate on said housing, said bolt when released permitting said retaining plate to move to the extent of said slot out of engagement with said pivoted member to permit the same to be withdrawn downwardly out of its aperture.

13. A bottle capping device including a housing having a pair of upright apertures formed therein, a plunger movable vertically in one of said apertures, a pivot member arranged to oscillate in another of said apertures and con-

- nections between said plunger and said pivot member for producing oscillation of said pivot member when said plunger reciprocates, cap feeding means actuated by said pivot member, a plate 5 engaging the upper portion of said pivot member for preventing movement of said pivot member out of its aperture, said plate having a slot, and a bolt extending through said slot and secured in said retaining plate on said housing, said bolt 10 when released permitting said retaining plate to move to the extent of said slot out of engagement with said pivoted member to permit the same to be withdrawn downwardly out of its aperture, and means on said plunger adapted to engage 15 said retaining plate when the same is in its operative position to prevent withdrawal of said plunger out of its aperture.
14. A bottle capping device including a housing having a pair of upright apertures formed 20 therein, a plunger movable vertically in one of said apertures, a pivot member arranged to oscillate in another of said apertures and connections between said plunger and said pivot member for producing oscillation of said pivot member 25 when said plunger reciprocates, cap feeding mechanism operated by said pivot member, means at the lower end of said pivot member for limiting the extent to which the same may be moved upwardly in its aperture, a head on said pivot member extending above the upper end of its aperture, a retaining plate arranged on the upper face of said housing and having a part engaging said head, a bolt for clamping said retaining plate to said housing, said retaining plate 30 being arranged to swing about said housing at a point intermediate between said bolt and the portion of said retaining plate engaging said head, and means on said retaining plate for limiting the extent to which the same may swing when 35 said bolt is tightened.
15. A capping device including a housing having an annular downwardly flaring skirt engageable with a bottle mouth of a certain outside diameter for guiding the bottle mouth into engagement with and centering the same in an internal seat to aline said bottle with a plunger movable axially to and from said seat for applying 40 a cap to said bottle, and a detachable adapter comprising an annular tapered member engageable within said skirt and having its upper end of a smaller diameter than the outer diameter of said seat to guide a bottle mouth of different external diameter into axial alinement with said plunger.
16. A capping device including a housing having an annular downwardly, flaring skirt engageable with a bottle mouth of a certain outside diameter for guiding the bottle mouth into operative alinement with a plunger for applying a cap to said bottle, and an adapter formed to be releasably secured within said skirt and which has an inner tapered face with which the 15 mouth of a bottle having a different external diameter is engageable for guiding such bottle into axial alinement with said plunger.
17. A capping device including a housing having an annular depending, flaring skirt engageable with a bottle mouth of a certain outside diameter for guiding the bottle mouth into operative alinement with a plunger for applying a cap to said bottle, and an adapter formed to be releasably secured within said skirt for guiding a 20 bottle having a mouth of a different external diameter into axial alinement with said plunger, hooks on said adapter engageable upon the outer face of said skirt for retaining said adapter in position thereon, and said skirt having a part 25 cut away from an edge portion thereof for the passage of one of said hooks upwardly therethrough after another hook has been operatively engaged with said skirt to enable said adapter to be turned and retained in position upon said 30 skirt.
18. An adapter for use with a bottle guiding skirt of a bottle capping device, to act as a centering guide for the mouth of a bottle for positioning the bottle in operative relation to 40 the capping device, comprising an annular tapered body, and hooks extending upwardly and inwardly from the lower edge thereof for connecting the adapter to the skirt of the bottle capping device.
